UNITED STATES PATENT OFFICE.

CHRISTOPHER BLAKE, OF BOSTON, MASSACHUSETTS.

CYLINDER-DESK.

SPECIFICATION forming part of Letters Patent No. 249,292, dated November 8, 1881.

Application filed October 18, 1880. (Model.)

To all whom it may concern:

Be it known that I, CHRISTOPHER BLAKE, a citizen of the United States, residing at Boston, in the county of Suffolk and State of Massachusetts, have invented an Improvement in Cylinder-Desks, of which the following is a full, clear, and exact description, reference being had to the accompanying drawings, making part of this specification, in which—

10 Figure 1 is a perspective view of a cylinder-desk constructed in accordance with my invention. Fig. 2 is a longitudinal vertical section through the same. Fig. 3 is a transverse vertical section on the line $\alpha\alpha$ of Fig. 2.

15 My present invention relates particularly to that class of desks well known as "cylinder-desks;" and it consists in the combination of a single lever with a single link for connecting the cylindrical top with the horizontal slide, 20 whereby the single operation of opening or closing one will open or close the other, as desired, the two pieces constituting this connection affording a construction of the greatest simplicity.

25 In the said drawings, A A represent the sides of the desk, between which is fitted the revolving top B, made in the form of a segment of a hollow cylinder, which, when closed or shut down, rests with its lower edge, 30 upon the slide or sliding table C, which forms, when drawn out, the writing-surface of the desk.

35 The top B has secured to it at each end a radial arm or lever, D, which is pivoted at a to the contiguous side A, these two levers serving to support the top B, which reciprocates in the arc of a circle around the pivots a as a center, its backward motion being limited by stops 6.

40 To the lower end of the arm b of each lever D is pivoted one end of a link, E, the opposite end of which is pivoted at c to the adjacent edge or side bar of the slide C, and by means of these connections, as the top B is revolved or thrown back to open the desk by taking hold of the knob d , the levers D are reciprocated on their pivots a , and the sliding table C thus thrown out horizontally in the proper position to form a convenient writing-surface, and when the top B is rotated forward, or in 45 the opposite direction to close the desk, the slide C will be simultaneously drawn in out of

the way, as desired, a single movement only of the hand being required to throw back the top and push out the slide, or vice versa, instead of two separate movements, one to rotate the top and the other to move the slide, as has heretofore been necessary in desks of this description.

55 It is evident that the top may be rotated in either direction by taking hold of and moving the slide; but the usual method of opening the desk is by taking hold of and rotating the top B, while in closing it the rotation of the top is most commonly effected by pushing in the slide. The top, however, may be operated by 60 the slide, or the slide by the top, as may be found most convenient.

65 The rear portion of the desk is provided, as usual, with pigeon-holes or compartments and drawers, which are arranged within a quarto-cylindrical case, G, over which the top B is rotated as the desk is opened and closed.

70 A desk constructed as above described is simple, convenient, easily operated, and not liable to get out of repair, while it is exceedingly compact, thus especially adapting it for parlors, libraries, &c.

75 Instead of connecting both levers D with the slide C, one only may be connected therewith, the link E at the other side of the desk 80 being dispensed with. I prefer, however, to connect both levers with the slide, as shown, as it equalizes the strain and renders the parts less liable to get out of order.

85 I am aware that other lever-and-link connections have been employed for accomplishing the desired result—viz., the simultaneous opening or closing of both the top and the slide by the single application of one hand to either. For instance, one connection consists of a lever and two links and two pivots, one pivot 90 for the top, separate and independent of the pivot on which the lever is fulcrumed, the lever having a link at its upper end secured indirectly (by a segmental plate) to the cylindrical top, and a link at its lower end secured to the slide; but my connection shows the top supported by, not pivoted to, a lever, thus reducing the number of pivotal points, and with 95 but one link, being, as I believe, the least number of pieces for this purpose at present employed.

What I claim as my invention, and desire to secure by Letters Patent, is—

The combination, with the cylindrical top B and horizontal slide C, of the lever D and link E, the lever being pivoted at a, for supporting and admitting the movement of the top in an arc of a circle, and the link having its lower end pivoted to said lever and its upper end to the slide, whereby the simultaneous

opening or closing of both the top and slide is insured by a single application of the hand to either, substantially as described.

Witness my hand this 8th day of October, A. D. 1880.

CHRISTOPHER BLAKE.

In presence of—

P. E. TESCHEMACHER,
C. E. CUMINGS.
